UNITED STATES PATENT OFFICE

ALFRED T. JESTER, OF HOUSTON, TEXAS

REPEATER SYSTEM

Application filed November 6, 1931. Serial No. 573,417.

My invention relates to telegraph repeaters and has for its object the provision of certain improvements in repeaters adapted to repeat both ways whereby improved efficiency in transmission may be obtained.

More particularly my invention contemplates the provision of a repeating device having a plurality of electro-magnetic elements arranged in pairs each such element having a coil and the elements being so arranged that one of the coils of the pair of elements will attract a common armature of both elements, this coil, however, having such a high resistance that the current necessary for the energization of this coil will not be sufficient to energize any of the relay sounders on the telegraph line, the coil of the other element of the pair being so arranged under the control of the sending keys as to by-pass the high resistance coil and maintain the armature attracted to thereby transmit the impulses toward the other end of the line.

I will explain my invention in detail by reference to the accompanying drawing in which—

Fig. 1 is a diagrammatic representation of the repeater associated with the telegraph line;

Fig. 2 is a similar representation showing a modified form of the repeater circuit; and

Fig. 3 illustrates a further modification embodying the invention.

Referring more particularly to Fig. 1, I show a repeating station A as adapted to repeat messages between two oppositely extending telegraph lines marked 1 and 2, respectively, which telegraph lines may be provided, of course, with one or more of the ordinary series telegraph sets. One station only for each line is shown, however, these being referred to as stations B and C, respectively. These stations serve to indicate the character of the apparatus at each of such ordinary telegraph stations. The line 1 is provided with the usual telegraph relay 3 which controls the customary sounder (not shown), the sending key 4 and battery 5 connected to ground at 6. The line 2 is provided with similar apparatus consisting of relay 7,

sending key 8, and battery 9, grounded at 10. At the repeating station I have a pair of armatures 11 and 12 provided with front contacts 13 and 14, respectively. Retractile springs 15 and 16 retract these armatures. 55 Armature 11 is attracted by the two electromagnets 17 and 18 having coils 19 and 20, respectively, coil 19 being a holding coil and preferably having a very high resistance, for example about 100,000 ohms. Armature 12 is attracted by the two electromagnets 21 and 22 having coils 23 and 24 thereon. Coil 23 is high resistance holding coil like 19. Coils 20 and 24 are relatively low resistance line coils of a standard low resistance such as 150 ohms. Line 1 is connected directly to coils 19 and 20, and line 2 is connected directly to coils 23 and 24. The free end of coil 19 is connected over line 25 and through battery 26 to ground at 27. Armature 12 is 70 also connected to battery 26. The free end of coil 23 is connected over line 28 through battery 29 to ground at 30. Armature 11 is also connected to battery 29. The free end of coil 20 is connected by conductor 31 to 75 contact 14, and the free end of coil 24 is connected by conductor 32 to contact 13. Conductor 33 connects coils 19 and 20, while conductor 34 connects coils 23 and 24.

In Fig. 2, the wiring connections and parts 80 are much the same as in Fig. 1. However, in Fig. 2 the line wire 1' connects to one end of coil 20' while conductors 31' and 33' connect to the other, and line wire 2' connects to one end of the coil 24' while conductors 85 32' and 34' connect to the other. The difference in operation will be brought out later.

In Fig. 1, assuming key 4 to be open and key 8 to be closed which is the position of sending from B and repeating at C, then 90 current flows from battery 9 through key 8, relay 7, line 2 to coil 23, and through coil 23 over conductor 28 to battery 29 and ground at 30. This causes electromagnet 21 to attract armature 12. But on account of 95 the extremely high resistance of coil 23, the current in line 2 is well below that necessary to cause relay 7 to attract its armature and operate the sounder. Armature 12, however, closes contact at 14.

Now when key 4 is closed, a closed circuit is established from ground 6, through battery 5, key 4, coil of relay 3, line 1, conductor 33, coil 20, conductor 31, contact 14, and armature 12 to battery 26 and ground at 27. This closes armature 11 to contact 13 and shunts coil 23 across coil 24 by connecting battery 29 through armature 11, contact 13, conductor 32, coil 24, and conductor 34 to line 2. 10 This path allows sufficient current to flow to operate relay 7. Electromagnet 22 holds armature 12 while coil 23 is shunted so that armature 12 cannot drop back away from 14 and break the holding circuit for armature 11.

With the system as above described, the holding coils being practically independent of the other coils may have very high resistance and many turns. This permits the use 20 of more turns on the line coils and thus improves transmission. The action when key 4 is closed and key 8 is sending is the same as just described, but it is in reverse order.

In the form shown in Fig. 2, the differences 25 in connection have already been pointed out. Assuming as in the case just described with Fig. 1 that key 8' is closed so that relay 7' is receiving, coil 23' is energized over the line indicated by the arrows. The current 30 which will flow through the high resistance coil 23' is insufficient to effect relay 7' or to cause sufficient energization of 24' to enable it to hold armature 12' closed. Now if key 4' is depressed closing the circuit, coil 20' is 35 immediately energized and attracts its armature 11' so as to close the circuit through from battery 29' over armature 11', contact 13', conductor 32', coil 24', line 2', relay 7', key 8', and battery 9' to ground at 10'. This 40 is a low resistance circuit as is readily seen and therefore will permit enough current to flow to actuate relay 7' as in the case with the diagram shown in Fig. 1. Coil 23', however, instead of being shunted across the low resistance coil as in Fig. 1 is now short circuited because conductors 34' and 32' are connected through contact 13', armature 11', to conductor 28' direct, thus completely short circuiting coil 23' while coil 24' maintains 45 the armature 12' attracted. When key 4' is again opened, the short circuit for coil 23' is broken at 13' by the deenergization of relay 18' so that coil 23' will again be energized as before to hold the armature 12' in 50 closed position. When the sending is reversed so that station B is receiving, coil 19' is short circuited out in the same manner as coil 23'.

In Fig. 3, the coils 19'' and 20'' operate 55 for repeating on a branch line 1''. This system is particularly useful in repeating to and from a duplex set. It utilizes a half set in conjunction with a repeating sounder or any other type of relay having an armature and a single contact point such as indicated at

35. The closing of the distant duplex line will cause the relay 35 to close which in turn closes armature 36 on contact 37, and, if the key 38 is then closed, armature 39 will make on contact 40 and thus the pole changing relay will close. This type of construction shown in Fig. 3 also shows means whereby the resistance of the holding coil 19' may be varied without rewinding. Suitable external resistances such as 41 and 42 are provided on the holding coil for this purpose. It is obvious that these resistances may also be similarly applied in the forms shown in Figs. 1 and 2.

From the above description, it is believed 80 that the construction and operation of this device will be clear to those skilled in this art and the advantages thereof readily apparent.

Having thus described my invention, what 85 I claim as new and desire to secure by Letters Patent is:

1. A telegraph repeating system consisting of two telegraph lines, a pair of electromagnetic devices for each line each having 90 a coil, said devices controlling a common circuit point in their respective lines, one of said devices for one line when actuated actuating its armature to establish a circuit to repeat impulses to the other telegraph line 95 through the coil of one only of the pair of devices of said other telegraph line, the other of said last named pair of devices serving for relay energizing purposes and being electrically connected to the telegraph line. 100

2. A telegraph repeating system consisting of two telegraph lines, a pair of electromagnetic devices for each line having an armature to repeat impulses to the other telegraph line through the winding of one of the electromagnetic devices of said other telegraph line, the winding of the other electromagnetic device of each line having a resistance sufficient to prevent energization of 105 telegraph relays of its associated line in 110 series therewith, but sufficient ampere turns to attract its associated armature with such energization.

3. A telegraph repeating system consisting of two telegraph lines, a pair of electromagnetic devices for each line having an armature to repeat impulses to the other telegraph line through the winding of one of the electromagnetic devices of said other telegraph line, the winding of the other electromagnetic device of each line having a resistance sufficient to prevent energization of 115 telegraph relays of its associated line in 120 series therewith, but sufficient ampere turns to attract its associated armature with such 125 energization, said high resistance winding being shunted across the winding of the other of said pair of devices when impulses are being repeated.

4. A telegraph repeating system consist-

ing of two telegraph lines, a pair of electro-
magnetic devices for each line having an
armature to repeat impulses to the other
telegraph line through the winding of one
5 of the electromagnetic devices of said other
telegraph line, the winding of the other elec-
tromagnetic device of each line having a
resistance sufficient to prevent energization
of telegraph relays of its associated line in
10 series therewith, but sufficient ampere turns
to attract its associated armature with such
energization, said high resistance winding be-
ing short-circuited by the energization of
the winding of the other of said pair of de-
15 vices when the repeater is operating.

In witness whereof, I hereunto subscribe
my name this 30 day of October, A. D. 1931.

ALFRED T. JESTER.
